UNITED STATES PATENT OFFICE.

CHARLES R. LAMBERT, OF DETROIT, MICHIGAN, ASSIGNOR TO CLAYTON & LAMBERT MANUFACTURING COMPANY, OF DETROIT, MICHIGAN, A CORPORATION OF MICHIGAN.

PROTECTING-BASE FOR FLUID-HOLDING TANKS.

1,298,968.

Specification of Letters Patent.

Patented Apr. 1, 1919.

Application filed February 5, 1917. Serial No. 146,620.

To all whom it may concern:

Be it known that I, CHARLES R. LAMBERT, a citizen of the United States of America, residing at Detroit, in the county of Wayne 5 and State of Michigan, have invented certain new and useful Improvements in Protecting-Bases for Fluid-Holding Tanks, of which the following is a specification, reference being had therein to the accompanying drawings.

The invention relates to fluid-holding tanks formed of sheet-metal, having more particular reference to constructions designed for use for holding liquid fuel in 15 small furnaces, torches, etc. It is the object of the invention to protect the tank from shocks and abrasions which might render the same leaky.

In the drawings:

20 Figure 1 is an elevation of a tank to which my improvement is applied;

Figs. 2, 3, 4 and 5 are sections showing modifications.

A is the tank, preferably comprising a 25 dome-shaped body portion formed of a drawn sheet-metal blank, and a bottom portion B having a depending flange C engaging an enlargement D at the base of the body and retained by the return-bent flange 30 E thereon. Tanks constructed in this manner have heretofore been extensively used, the seam between the flanged bottom and body being soldered or otherwise rendered liquid-tight, and also constituting a supporting base for the tank. It has been found 35 that tanks of this construction in the ordinary wear and tear of service frequently receive shocks or abrasions which cause a leak. To avoid this, I have provided a protecting 40 base of the following construction:

F is a band of sheet-metal surrounding the base portion D of the tank and having formed on its lower edge a bead G. The upper edge portion of the band is contracted 45 to fit over the shoulder H formed by the enlarged portion D of the tank, while the bead extends beneath and supports the depending flanged portion. Thus, in use, the flanged portion of the tank is protected from direct 50 injury, while the bead G forms the supporting base and receives all abrasion to which the tank is ordinarily subjected.

As shown in Fig. 2, the lower portion of the band F is flared outward, as indicated at I, forming a yieldable resilient portion for 55 receiving shocks. In Figs. 2, 3 and 5 the beaded edge G' is formed without core, while in Figs. 1 and 4 a wire core is inserted within the bead as a further reinforcement. In Fig. 4 the band is provided with an inwardly-extending return-bent flange J for supporting the tank, while the bead extends outward, and in Fig. 5 there is an inwardly-extending bead K for supporting the tank and an outwardly-extending bead G² forming 60 the supporting base. With all of the various modifications the surrounding band will protect the base so as to avoid injury thereto.

For engaging the protecting band with the 70 tank, it may be formed with a split therein, as indicated at L, and if desired the ends of the band may be overlapped and united by spot-welding or other means.

What I claim as my invention is:

1. The combination with a fluid-holding tank comprising a body portion enlarged at the base and a bottom portion with a depending flange fitting within said enlargement and forming a seamed connection therewith, of a protecting member formed of a sheet-metal band surrounding said enlarged base portion, the upper end of said band being crimped over the shoulder at the upper end of said enlargement, and the base of said 80 band being beaded and forming a support for the tank.

2. The combination with a fluid-holding tank, comprising a body portion enlarged in diameter at the base thereof and a bottom 90 portion having a depending flange fitting within said enlargement and seamed thereto, of a protecting member for said base, comprising a sheet-metal band surrounding said enlargement, the upper edge portion of said 95 band being crimped to fit over the shoulder formed by said enlargement, and the lower portion of said band being beaded and extending beneath said depending flange to support the same.

In testimony whereof I affix my signature.

CHARLES R. LAMBERT.
